UNITED STATES PATENT OFFICE

THOMAS A. CONLON, OF SILVER SPRING, MARYLAND

VARIABLE RECOIL MECHANISM FOR GUNS

Application filed October 28, 1929. Serial No. 403,077.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 This invention relates to a variable recoil mechanism for guns and particularly for that class of guns wherein a portion of the powder gases of discharge are utilized for retarding the recoil movement of the gun, 10 being compressed in this operation and made available for restoring the gun to battery.

The system of controlling the movement of a gun by means of powder gases, as proposed by McLean in Patent No. 749,215 15 templates the least possible movement of the gun in recoil, but the present invention is applicable to improvements in this gun which have a normal recoil appropriate to the maintenance and stability of the mount.

20 The invention consists in the provision and novel association of a variable recoil with one of the elements of the recoil mechanism.

With the foregoing and other objects in view, the invention resides in the novel arrangement and combination of parts and in the details of construction hereinafter described and claimed, it being understood that changes in the precise embodiment of the invention herein disclosed may be made within 25 the scope of what is claimed without departing from the spirit of the invention.

A practical embodiment of the invention is illustrated in the accompanying drawings, wherein:

30 Fig. 1 is a view partly in side elevation and partly in longitudinal section of a gun, embodying the improved variable recoil mechanism;

Fig. 2 is a view in side elevation, partly in 40 section, showing gun in full recoil;

Fig. 3 is a longitudinal sectional view through the forward end of the recoil mechanism;

Fig. 4 is a sectional view on the line 4—4 45 of Fig. 3;

Fig. 5 is a longitudinal sectional view through the rear end of the recoil mechanism; and

Fig. 6 is a sectional view on the line 6—6 50 of Fig. 5.

Referring to the drawings by numerals of reference:

There is shown a gun 5 mounted to slide through normal distances in a cradle 6 which is provided with the usual trunnion 7. A 55 cylinder 8 arranged parallel to the gun and secured thereto by means of a bracket 9 so that it will move with the gun, is open at its rear end to receive a hollow piston 10 fixed to the cradle 6. The head 11 at the forward end of the cylinder is formed with a chamber 12 which is in communication with the bore 13 of the gun through a passage 14, and with the cylinder through apertures 15, normally closed by a valve 16. 60

The inner end 17 of the hollow piston 10 is provided with a port 18, normally closed by a valve 19 carried on the end of a rod 20. The valve is formed with an aperture 21 designed to cover the port 18 and thereby regulate the volume of gas which is to be compressed in the cylinder 8. The rod 20 may be controlled manually or through a connection with the tipping parts, specifically by gearing 22 actuated from the trunnion 7. 70

In operation, when the gun is fired, a portion of the rapidly expanding gases of discharge will pass into the chamber 12, cause the opening of the valve 16 and be delivered into the cylinder 8 which by reason of its attachment to the gun is partaking of the recoil movement. 75

During the initial stage of recoil the pressures in the chamber 12 and in the cylinder 8 will have been equalized and the valve restored to its normally closed position. Thereafter the gases which are confined in the cylinder will be compressed as the cylinder head approaches the piston 10 and will act to yieldingly check the recoil of the gun and then restore the gun to its normal battery position. The effective volume of the gases in the cylinder as controlled by the valve 19 will have increased as the elevation of the gun 80 approaches the zenith. 90

A device for holding the gun in battery is contained in a cylinder 23 but its particular nature is not pertinent to the present invention. 95

I claim:

1. In a gun, a barrel mounted to recoil and counter-recoil through normal distances, a recoil cylinder movable with the barrel and having valved communication with the bore of the barrel to permit flow of gases from the barrel into the cylinder, a fixed piston working in the cylinder, a valve at the inner end of the piston regulating the volume of gas in the cylinder and means for moving the valve in accordance with the elevation of the barrel.

2. In a gun, a barrel mounted to recoil and counter-recoil through normal distances, a recoil cylinder movable with the barrel and having communication with the bore of the barrel to permit flow of gases from the barrel into the cylinder, a fixed piston working in the cylinder and means controlled by the position of elevation of the barrel for regulating the volume of gas in the cylinder.

3. In a gun, a barrel mounted to recoil and counter-recoil through normal distances, a recoil cylinder movable with the barrel and having communication with the bore of the barrel to permit flow of gases from the barrel into the cylinder, a fixed piston working in the cylinder and means for regulating the volume of gas in the cylinder.

4. A cradle, a gun reciprocally mounted thereon, a recoil mechanism embodying relatively movable parts, means for admitting gases of discharge to said mechanism to check recoil and restore the gun to battery, and means for regulating the volume of the utilized gases.

THOMAS A. CONLON.
